US00D556128S

(12) **United States Design Patent**
Miyakawa et al.

(10) Patent No.: **US D556,128 S**
(45) Date of Patent: **** Nov. 27, 2007**

(54) **OPTICAL TRANSMISSION CONVERSION
DEVICE**

(75) Inventors: **Takeshi Miyakawa**, Yokohama (JP);
Shigeyuki Sakura, Kawasaki (JP);
Motoyasu Morinaga, Chigasaki (JP)

(73) Assignee: **Kabushiki Kaisha Toshiba** (JP)

(**) Term: **14 Years**

(21) Appl. No.: **29/254,985**

(22) Filed: **Mar. 3, 2006**

(30) **Foreign Application Priority Data**

Dec. 5, 2005 (JP) 2005-035848

(51) **LOC (8) Cl.** **13-02**

(52) **U.S. Cl.** **D13/101; D13/123**

(57) **CLAIM**

The ornamental design for an optical transmission conversion device, as shown and described.

DESCRIPTION

FIG. 1 is a front, top and right side perspective view of an optical transmission conversion device, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.
